FREENESS TESTING APPARATUS

Clarence E. Miller, Covington, Va., assignor to West Virginia Pulp and Paper Company, New York, N.Y., a corporation of Delaware

Filed Oct. 19, 1965, Ser. No. 497,852

5 Claims. (Cl. 73—63)

ABSTRACT OF THE DISCLOSURE

In an in-line freeness testing device which is mounted on a papermaking stock line and measures freeness by intermittently drawing samples of the stock into a standpipe having a screen across its lower end and measuring the height to which the liquid rises in the standpipe in a given time, the sensitivity of measurements is increased without increasing the length of the standpipe or decreasing the volume of liquid sampled by using a standpipe having an upper portion of appreciably smaller cross-sectional area than its lower portion.

The present invention is directed to apparatus for testing the freeness of paper stock and more particularly, to apparatus of high sensitivity capable of indicating small changes in paper stock freeness.

In the manufacture of paper, a low consistency slurry of fibers and liquid is deposited on a foraminous surface and the liquid allowed to drain, leaving a loosely felted mat of fibers. This mat is thereafter subjected to pressing, driving, etc. to provide a finished paper web. Dependent to a great extent on the amount of refining to which the fibers are subjected is the rate at which the liquid will drain from the slurry. This characteristic is generally referred to as the stock freeness, or, its antonym, slowness. Thus, a very free stock is usually one in which the fibers have been subjected to little refining and as a result, the fibers are quite coarse and liquid will drain therefrom quite readily. Conversely, a slow stock is generally one in which the fibers have been subjected to a great deal of refining and in consequence, the fibers are fine, compact readily, and retard the rate of drainage of the liquid from the stock.

Aside from its obvious effect on process speed, it will be apparent that the freeness of a paper stock is also an indication of the quality of the paper which will be formed therefrom. It is therefore, highly desirable to monitor and control the freeness of the paper stock during the paper making operation.

Unfortunately, in the past, a method of checking paper stock freeness which was both quick and accurate did not exist. Thus, one common method of determining paper stock freeness is to withdraw a sample of the stock from the process and evaluate it in a laboratory. While the results are usually quite accurate, it will be obvious that the time interval between withdrawing a sample and evaluating it greatly detracts from the effectiveness of this method as a stock freeness control means.

More recently, apparatus has been designed which permits paper stock freeness testing on an in line basis. Thus, as shown in U.S. Patent No. 3,186,215, an elongated, hollow, standpipe is attached to a stock pipe line with a piece of screen or the like secured across its inlet end adjacent the pipe line. The other end of the standpipe is closed and connected to a source of variable pressure. With this arrangement, it will be seen, the interior of the standpipe may be kept under sufficient pressure to prevent the stock from rising up into the standpipe. At preselected intervals however, this interior pressure is reduced sufficiently to allow the stock to flow into the standpipe, the majority of the fibers in the stock being filtered out by the screen-

2

ing across the standpipe inlet. By either maintaining the reduced pressure for a set time period and observing the height to which the stock rises in the tube during that time, or allowing the stock to rise to a preselected height in the standpipe and measuring the time required for it to rise to that height, an indication of the freeness of the stock can be obtained.

One difficulty that has been experienced however, is that the small changes in stock freeness that will usually occur under normal operating conditions are not readily discernible with this instrument; yet these small changes will have an appreciable effect on the papermaking process. Thus, a fairly large change in freeness will result in only a very small change of liquid column height. To remedy this it has been suggested that the internal diameter of the standpipe be reduced. In this way a change in freeness and hence, a change in the volume of liquid entering the standpipe, will be reflected as an appreciable change in liquid column height. It will be apparent though, that if the diameter of the standpipe is reduced, the length thereof must be increased in order to accommodate the same volume of liquid. In practice however, it has been found that in order to decrease the diameter of the tube to a point where significant changes in liquid column height are observable and at the same time retain the original capacity of the standpipe, the length of the standpipe must be increased to an extent which is impractical in a commercial environment.

Another approach to increasing the sensitivity of the unit described above has been to decrease the tube diameter, retain its original length, and shorten the sampling time, or the time in which liquid is allowed to rise in the standpipe, so that the volume of liquid which the tube must accommodate is decreased. Again, while this solution appears attractive in theory, it has been found in practice that if the sampling time is decreased to an extent sufficient to give the desired smaller volume, the resulting short sampling times do not permit the accumulation on the inlet screen of a pad of fibers of sufficient thickness to give meaningful results.

It will be seen from the above, that while sampling and laboratory testing provides an accurate method of checking stock freeness and in line testing is quick and convenient, neither method combines accuracy with speed and ease of operation.

It is therefore, an object of the present invention to provide means for quickly, accurately and automatically monitoring the freeness of paper stock or the like on an in line basis. This has been accomplished as a result of applicant's observation that although most commercially available equipment is capable of indicating freeness variations over a fairly wide range of values, only relatively small changes will usually occur in a commercial operation. Therefore, in a practical context, it is only necessary that the testing equipment be highly sensitive over this relatively narrow range in order to obtain consistently accurate readings.

On the basis of these observations applicant has devised means for improving the sensitivity of prior art testing apparatus without increasing standpipe length or reducing normal sampling time. Thus, it is a specific object of the present invention to increase the sensitivity of prior art freeness testing apparatus without sacrificing their convenience and ease of operation.

These and other features and objects of the present invention will become more readily apparent from the following detailed description wherein:

FIGURE 1 is an elevational view, partly in section, of an embodiment of the present invention; and

FIGURES 2 and 3 are illustrations of alternate embodiments of the invention.

With reference to FIGURE 1 it will be seen that the improved freeness testing unit may comprise an elongated, hollow member 1 formed in two main sections 2 and 3 joined by a transition section 4. A suitable fitting 5 attaches the member 1 at its inlet end to a stock pipe line 6 and a cap member 7 serves to close off the opposite end of member 1. As seen in FIGURE 1, section 2 of member 1 extends from the inlet end towards the closed end thereof and is of substantially greater cross sectional area than any portion of section 3. A piece of screening or the like 8 of a suitable mesh covers the inlet end of member 1 and a pressure line 9 in conjunction with a pair of branch lines 10 and 11 provides means for selectively pressurizing or depressurizing the interior of member 1. Lines 10 and 11 each pass through a timer unit 12 and thence, to a pressure source and a source of vacuum or atmosphere, respectively. A pressure cell 13 is attached to member 1 adjacent its inlet end and signals received by cell 13 are transmitted for recording to a recorder 14.

In operation, the interior of the member 1 may be kept under sufficient pressure by means of lines 9 and 10 to prevent the stock 15 from rising up into member 1. At preselected intervals however, timer unit 12 closes off line 10 and through lines 9 and 11 provides a sufficiently reduced pressure within member 1 to allow the stock to flow thereto. Timer unit 12 may be adjusted to maintain this reduced pressure for a preset sampling time, and at the end of this period, the interior of member 1 is again pressurized, forcing the stock liquid back into the pipe line 6 and flushing off the pad of fibers which has collected on screening 8. Recording unit 14, through signals received from pressure cell 13, has meanwhile recorded the maximum pressure which occurred in the member during the period of reduced pressure.

As noted previously, in prior art apparatus of this type a constant diameter tube or standpipe was used, and in order to maintain the length of the tube within reasonable limits and at the same time permit the accommodation of a sufficient volume of liquid in the standpipe to allow a pad of fibers to build up on the screened inlet, the diameter of the tube was fairly large. However, with a large diameter tube, an appreciable change in freeness and hence, a proportionate change in the volume of the liquid entering the tube, resulted in very little change in liquid column height.

By means of the present invention however, it will be seen that the relatively large cross sectional area of section 2 allows a large enough volume of liquid to be accommodated in member 1 to permit the build up of a pad of fibers on screen 8 of sufficient thickness to give meaningful readings. At the same time, the overall length of member 1 need not be increased. On the other hand, in section 3 of member 1, a relatively small change in the volume entering this section will result in an appreciable change in liquid column height. Since, as a practical matter the changes in freeness which will normally occur will be quite small and hence, the changes in the volume of liquid entering member 1 quite small, member 1 can readily be dimensioned so that the termination of a sampling cycle will occur while the liquid level is within section 3. Since the pressure sensed by cell 13 is determined by liquid column height, irrespective of volume, the reduced cross sectional area of section 3 provides an extremely sensitive indication of changes in the volume of liquid passing into member 1 and hence, of the freeness of the stock in pipe line 6.

While for simplicity of manufacture a configuration such as that shown in FIGURE 1 will usually be preferred, it will be apparent that the elongated, hollow member 1 may take a variety of shapes within the scope of the invention. For example, as seen in FIGURE 2, substantially spherical section 2a of member 1a has a portion of substantially greater cross sectional area than any portion of cylindrical section 3a. As a result, a large

volume of liquid may be accommodated in member 1a, as in member 1, yet relatively small changes occurring towards the end of the sampling cycle are reflected as relatively large changes in liquid column height by the reduced cross sectional area of section 3a.

Similarly, while the relatively large cross sectional area of at least a portion of section 2b, FIGURE 3, permits a large volume of liquid to be accommodated by the elongated, hollow member 1b, relatively small changes in volume occurring in section 3b will result in readily discernible changes in pressure readings on a recorder of the type shown in FIGURE 1.

From the foregoing it will be apparent that applicant has improved the sensitivity of prior art freeness testing apparatus in a manner such that its convenience and ease of operation are not reduced. While certain specific examples of the invention have been described for purposes of illustration, modifications thereof will readily occur to those skilled in the art within the scope of the appended claims.

I claim:

1. In apparatus for testing the freeness of paper stock, including a standpipe with an open lower end, a horizontal screen mounted across the base portion of said standpipe for separating the fibers from the liquid of said paper stock, means connected to said standpipe for reducing the pressure therein and causing liquid from said paper stock to rise into said chamber while said fibers form a mat on said screen, and means for measuring the rate at which said liquid rises into said standpipe through said screen as an indication of relative stock freeness, the improvement comprising:

(a) said standpipe being formed in at least two sections,

(b) a first of said sections extending from said open lower end toward the opposite end thereof,

(c) the other of said sections extending from said opposite end toward said open lower end,

(d) at least a portion of said first section being of substantially greater cross-sectional area than said other section.

2. The apparatus of claim 1 wherein:

(a) both of said sections are substantially cylindrical, and

(b) the internal diameter of said first section is substantially larger than the internal diameter of said other section.

3. The apparatus of claim 2 wherein:

(a) a hollow, tapered transition section interconnects said cylindrical sections.

4. The apparatus of claim 1 wherein:

(a) said first section is substantially spherical in shape,

(b) said other section is substantially cylindrical in shape, and

(c) the internal diameter of said first section is substantially larger than the internal diameter of said other section.

5. The apparatus of claim 1 wherein:

(a) said first section tapers from a maximum internal dimension adjacent said open, inlet end to a minimum internal dimension adjacent said other section,

(b) said other section is substantially cylindrical in shape, and

(c) said minimum dimension and the internal diameter of said other section are substantially the same.
